UNITED STATES PATENT OFFICE.

EHME H. BIENHOFF, OF KENSINGTON, KANSAS.

WELL-CASING.

1,110,284.

Specification of Letters Patent. Patented Sept. 8, 1914.

Application filed January 6, 1914. Serial No. 810,613.

To all whom it may concern:

Be it known that I, EHME H. BIENHOFF, a citizen of the United States, residing at Kensington, in the county of Smith and State of Kansas, have invented new and useful Improvements in Well-Casings, of which the following is a specification.

The invention relates to a well casing designed for use in deep well boring.

10 The main object of the present invention is the provision of a well casing made up of a series of blocks cemented to form a tubular body and upper and lower sections connected to each other and acting as a reinforcing element for the body and as a means for securing the blocks against independent movement, each of the blocks being provided with screen openings for the usual purpose.

20 The invention in the preferred form, of details will be described in the following specification, reference being had particularly to the accompanying drawings; in which:—

25 Figure 1 is a perspective view of one section of the casing. Fig. 2 is a vertical central section of the same. Fig. 3 is a perspective of one of the blocks of which the casing wall is constructed. Fig. 4 is a perspective of one of the connecting rings. Fig. 5 is a perspective of the casing head. Fig. 6 is a perspective of one of the screen sections. Fig. 7 is an enlarged broken sectional view illustrating particularly the 35 screen formation.

With particular reference to the accompanying drawings, the improved well casing comprises a tubular main section 1 which in this instance is made up of a series of superimposed vertically offset cement blocks 2, which blocks are suitably curved to form the section of the desired diameter when the blocks are arranged in proper relative positions. Each block is formed with an elongated opening 3 adjacent each end thereof, the outer surface of the block surrounding the edge of each opening 3, being formed with a depression 4 to receive a screen.

50 The screens, one of which is used for each opening 3, comprise plates having an edge formation conforming to the depression 4 so that they may be seated therein to close the opening 3. The plates 5 are formed with transverse ribs 6 to strengthen the plates, being further formed with longitudinal slits 7 providing the screen. On the

inner surface each plate 5 is provided with a longitudinally extending rod 8 movably connected to the plate through the medium of tie straps 9, the ends of the rod being bent at right angles to the plate and formed with hook terminals 10. The plates are secured in place by being seated in the depressions 4 and the hook terminals 10 engage beneath or against the inner walls of the openings 3, as will be plain from the drawings.

In connection with the casing section described, I provide a shoe for the lower end thereof, this shoe being designed to aid in fitting the casing downward as the sand and earth are removed from the interior of the casing. The improved shoe comprises a metallic ring 11 of appreciable height and sufficient thickness to insure a structure of the proper weight. The ring is of greatest thickness at its upper edge, so that at said upper edge it presents a comparatively broad bearing surface 12, the inner and outer surface of the side wall of the ring being projected from the inner and outer edges of the bearing surface on slight outwardly curving lines, the degree of curvature of the inner surface being greater than that of the outer surface so that said surfaces meet at the lower edge of the ring in comparative coincidence, presenting a comparatively thin cutting edge 13. The cutting shoe described is formed with radially projecting lugs 14 coincident with the bearing surface and extending beyond the outer surface of the rim. 90

A connecting plate 15 in the form of a flat ring is arranged upon the upper end of the casing, the said ring being formed with radial lugs 16 arranged in accordance with the lugs on the shoe. With the shoe and connecting ring in place the lugs 14, 16 are connected by tie rods 17 joining the vertically aligned lugs and brace and truing rods 18 connecting the offset or diagonally inclined lugs. By means of the rods 17 and 18 the respective blocks of the casing are secured against the possibility of independent movement and the casing as a whole is held intact.

The casing as an entirety is made up of a plurality of casing sections such as described, the connecting ring at the upper end of one casing section serving as a base or support for the lower edge of the immediately superimposed section. 105

110 The use and advantages of the improved construction will be readily apparent from

the above description taken in connection with the drawings, it being understood that as the earth or sand is cut from the interior of the casing, the latter will be lowered by gravity and the opening thus formed the shoe 11 readily forcing its way through any irregularities of the cut and insuring the proper drilling of the well without regard to the complete sandy character of the soil.

10. What is claimed is:—

1. A well casing section comprising an annular wall made up of blocks arranged in superimposed relation, each of said blocks being formed with an opening, and a screen removably secured in the opening.
2. A well casing section comprising an annular wall made up of blocks arranged in superimposed relation, each of said blocks being formed with an opening, and a screen removably secured in the opening, said screen being formed with projections having hook terminals to extend through the opening and engage the inner surface of the block.
3. A well casing section comprising an annular wall made up of blocks arranged in superimposed relation, each of said blocks being formed with an opening, a screen removably secured in the opening, and a driving shoe having a relatively broad bearing surface to receive the lower row of

blocks and a cutting edge arranged below said bearing surface.

4. A well casing section comprising an annular wall made up of blocks arranged in superimposed relation, each of said blocks being formed with an opening, a screen removably secured in the opening, a driving shoe having a relatively broad bearing surface to receive the lower row of blocks, and a cutting edge arranged below said bearing surface, said cutting edge being arranged beyond the bearing surface.

5. A well casing section comprising an annular wall made up of blocks arranged in superimposed relation, each of said blocks being formed with an opening, a screen removably secured in the opening, a driving shoe having a relatively broad bearing surface to receive the lower row of blocks, a cutting edge arranged below said bearing surface, a connected plate bearing upon the upper edge of the section, tie rods uniting said bearing plate and shoe, and brace rods uniting said rod and shoe.

In testimony whereof I affix my signature in presence of two witnesses.

EHME H. BIENHOFF.
